UNITED STATES PATENT OFFICE

162,212

AUTOMOBILE REARVIEW MIRROR

Dwight M. Nelson, Chicago, Ill.

Application December 31, 1949, Serial No. 6,943

Term of patent 14 years

(Cl. D14—6)

To all whom it may concern:

Be it known that I, Dwight M. Nelson, a citizen of the United States, residing at Chicago, State of Illinois, have invented a new, original, and ornamental Design for an Automobile Rear View Mirror, of which the following is a specification, reference being had to the accompanying drawing, forming a part hereof.

Fig. 1 is a perspective view of an automobile rear view mirror showing my new design.

Fig. 2 is a rear perspective view thereof.

Fig. 3 is a plan view thereof.

The characteristic features of my new design reside in the supporting arm and its association with a mirror as shown in solid lines in the drawing.

I claim:

The ornamental design for an automobile rear view mirror, as shown and described.

DWIGHT M. NELSON.
